D11-161.

OR D11,797 EX

DESIGN.

—
J. ROGERS.
Group of Statuary.

No. 11,797.

Patented June 1, 1880.

*C. B. Arnold John Rogers.
J. Brantigan*

UNITED STATES PATENT OFFICE.

JOHN ROGERS, OF NEW CANAAN, CONNECTICUT.

DESIGN FOR A GROUP OF STATUARY.

SPECIFICATION forming part of Design No. 11,797, dated June 1, 1880.

Application filed April 5, 1880. Term of patent 14 years.

To all whom it may concern:

Be it known that I, JOHN ROGERS, of New Canaan, Fairfield county, and State of Connecticut, have originated and designed a Group 5 of Statuary, of which the following is a full, clear, and exact description, reference being had to the accompanying photographic illustration, making part of this specification.

The group is composed of four figures, and 10 represents Shylock, Portia, Antonio, and Bassanio at the trial scene in Shakespeare's play of the "Merchant of Venice." On the base of the group is quoted the remark of Shylock when Portia urges him to have a surgeon by, 15 "Is it so nominated in the bond?" A staircase is represented in the center, which is supposed to lead up to the duke's seat. Portia is on this stairway, dressed in lawyer's robes and square cap. She holds the bond in her 20 right hand, and is looking toward Shylock on her left with an appearance of entreaty. Shylock stands on the floor, dressed in long robes. In his left hand are seen the scales, and with his right hand he is pointing to the bond, and 25 looking up at Portia, while he asks the question quoted on the base. Opposite to him stands Antonio, who is dropping off his cloak in preparation for losing his pound of flesh. He stands on the floor with his left foot resting on the first step of the stairway. In front 30 of him stands Bassanio. His left hand is resting on Antonio's shoulder, and in his right hand is a bag of gold, which he has just offered to Shylock to pay the debt, but which he has refused.

35

What I claim as my invention is—

The design for a group of statuary, consisting of the representation of a female figure arrayed in lawyer's robes, standing upon a stairway, and the figure of an old man below, 40 and on one side, apparently in the act of pleading with the main figure, and on the other side two male figures, one holding a bag of money and the other in the act of divesting himself of his cloak, the words "Is it so nominated in the bond?" being presented on the base, substantially as described, and shown in the accompanying photographic illustration.

45 JOHN ROGERS.

Witnesses:

C. B. ARNOLD,
A. BRAUTIGAM.